UNITED STATES PATENT OFFICE.

ISAIAH L. ROBERTS, OF NUEVA GERONA, ISLE OF PINES, WEST INDIES, ASSIGNOR OF
ONE-HALF TO WILLIAM C. LICHTENSTEIN, OF JERSEY CITY, NEW JERSEY.

PROPELLER.

1,323,102.

Specification of Letters Patent. Patented Nov. 25, 1919.

Application filed April 18, 1918. Serial No. 229,356.

To all whom it may concern:

Be it known that I, ISAIAH L. ROBERTS, a citizen of the United States, residing at Nueva Gerona, in the Isle of Pines, West Indies, have invented certain new and useful Improvements in Propellers, of which the following is a specification.

The invention relates to rotary propellers especially suitable for navigation, either 10 marine or aerial, but equally useful in other devices and machines, such as turbine motors, pumps, blowers, etc. The propeller of the present invention is especially suitable, however, for the propulsion of boats and ships.

Heretofore, practically all of the propellers used in marine navigation have been 15 designed on the principle of the screw or variations thereof. These forms, as is well known, give an efficiency of driving-thrust 20 far below one hundred per cent., since no twist of a radial blade has been discovered which will enable the blade in its rotation about a center in passing through the water to produce a theoretically perfect thrust at 25 all points thereof at the same time. That portion of the blade near the hub and extending outward to a point approximately half way to the tip yields little or no thrust, according to the speed forward of the vessel, but consumes a considerable portion of 30 the power applied thereto, merely producing a churning action in the water when the speed of the ship is less than that for which the twist of the blade is calculated, 35 or acting by its retarding action as a brake if the speed of the ship is higher than that for which the twist given this portion of the blade is calculated. The efficiency of a 40 blade of a screw-propeller begins at a point some distance from the hub, the distance varying according to the speed of the vessel, and increases gradually to the tip of the blade.

In order to avoid the difficulties attending 45 the use of the screw, numerous deviations from the form of the original or true screw-propeller have been suggested, such as variations in curvature of the blades or in inclination, etc., but all of these so far as I am 50 aware still adhere to the screw as the basic principle and none known to me has exceeded in efficiency in practice the twisted and well-proportioned simple plane.

In my invention, I have departed from 55 the principle of the true screw and devised

a propeller along new lines which is of higher efficiency than any now known to me, the high efficiency obtaining alike at high or low speeds, and one in which propelling-thrusts are produced at all points 60 along the working-faces of the blades.

An embodiment of the invention is illustrated in the accompanying drawings, wherein—

Figure 1 is a plan view of the propeller; 65

Fig. 2 is a rear elevation;

Fig. 3 is a rear view in perspective;

Fig. 4 represents a section of one of the 70 blades of the propeller along the line A—B, Fig. 2, somewhat enlarged;

Fig. 5 shows a similar section through the line C—D, Fig. 2;

Fig. 6 shows an enlarged section of the 75 blade along the line E—F; and

Fig. 7 is a like section along the line G—H.

In the drawings, 1 represents the hub or boss of the propeller by means of which the latter is secured on the propeller- or driving-shaft of the craft. The blades are indicated at 2 and there are preferably three of them, as shown. 80

Each of the blades is so shaped that in a rear elevational view, as shown in Fig. 2, the leading-edge 3 describes a complete semi-circle while the trailing-edge 4 describes a semi-circle approximately concentric with the first, and between the two there is formed a semi-circular band terminating at one end in the hub 1 and at the other 90 in the blade-tip 5 which lies in a plane bisecting the hub 1. The center of the circle defined by the leading-edge 3 when viewed from the rear also lies in this plane and at a point half way between the far end of 95 the tip 5 and the far extremity of the aligned diameter of the hub.

The front- or thrust-face of the portion of each blade between the section line A—B and the boss 1 is uniformly curved, or concave, as shown in Fig. 4, this curvature varying, of course, with the size of the propeller, etc. In the example given, a sixteen inch propeller, which is quite suitable for driving a boat at a speed of ten or twelve miles an hour, is represented, and for a propeller of this size I have found a radius of curvature of one and three-quarters inches, i. e. a diameter of three and one-half inches, to be most suitable. The width 110

of this portion of the blade 2 is determined by the length of the arc of the three and one-half inch circle which subtends an angle of seventy-five degrees, *i. e.* a quarter circle minus fifteen degrees. The line A—B which is the limit of this uniformly concaved portion of the blade is the radial line of the semi-circular leading-edge 3, drawn through the point B' where a circle whose radius is one-fourth the over-all diameter of the propeller,—four inches in the propeller illustrated,—and whose center is the center of the hub, intersects the trailing-edge 4.

10 Beyond the line A—B, the concavity of the blade 2 diminishes gradually, or, in other words, the curvature flattens more and more as the hub 1 is left, until at the tip 5 there is no curvature and a substantially straight edge results, as clearly appears in Figs. 2 and 3. Sections through this portion of varying curvatures are illustrated in Figs. 4 to 7. At A—B, Fig. 4, the diameter of the curvature is still three and one-half inches; 20 at C—D, Fig. 5, which is half way between A—B and tip 5, the radius of curvature is substantially doubled, so that the diameter here is approximately seven inches; at E—F, Fig. 6, which is half way between A—B and 25 C—D, the curvature is the mean of the curvatures at these two sections or approximately five and a quarter inches in diameter; while at G—H, Fig. 7, the curvature has a diameter of approximately fourteen inches. 30 35 In other words, the variation in the curvature of this part of the blade is as regular as practicable and increases in the propeller illustrated from an arc A—B of seventy-five degrees of a circle whose diameter is three and one-half inches to an arc of a circle whose diameter is infinity, that is, a straight line.

The portion of the blade from the section A—B to the hub 1 lies in the transverse 40 plane of the hub, *i. e.* in a plane at right angles to the axis of the hub, as more clearly shown in Fig. 1. From the section A—B, however, the blade begins to bend rearwardly. The bend is gradual at first but 45 more pronounced as the curvature of the rear face flattens out, until a point about two-thirds of the length of the trailing-edge is reached, approximately along the line C—D, Fig. 2, where the bend becomes quite 50 abrupt and makes substantially a right-angle with the initial plane of the blade, when viewed from the top or sides of the propeller, as in Fig. 1. In other words, the portion of the blade from approximately 55 the line A—B to the tip 5 is bent backward on a straight incline. The amount of this incline determines the pitch of the propeller or the distance forward it should travel in the water without resistance or slip during 60 one complete revolution, and should be

matched with the speed it is intended the boat should have. The inclined portion of the blade should extend, whatever the pitch may be, until the tip lies in the plane of the axis of the hub, as above described, so that 70 the whole blade with its corresponding sector of the hub, when viewed from the rear, defines a semi-circular band. The length of this outer portion of the blade which determines the pitch of the propeller will depend 75 then upon the curvature gradient of the rear or thrust-face of the blade, and this in turn varies, of course, with the effective area or "disk" of the propeller.

The angular relation of the curved portion of the blade with respect to the axis of the hub is such that the water acted upon by the curved face leaves the trailing-edge 4 in lines parallel to the axis of the shaft. This being the case, and the arc of the curvature 85 of the blade being less than a quarter circle, the leading-edge will be so disposed as to cut its way unimpeded into the water. To continue the arc of curvature forward to the full ninety degrees would be to lessen the entering or forward-cutting tendency of the leading edge of the blade and to increase the resistance to the passage of the propeller through the water without increasing the propelling action, especially at high boat-speeds, should the propeller-speed not match. 90 95

The thickness of the blade is much greater at the rear or trailing-edge than at the leading-edge and this thickness diminishes as 100 the tip is approached. The leading edge is comparatively sharp and its thickness varies but little if at all. The increased thickness at the trailing-edge is for the purpose of strength and rigidity and the degree thereof 105 depends therefore upon the size of the propeller, its dimensions, the power applied, character of use, etc.

The rear edge 6 of the blade adjacent the trailing edge is preferably so located with 110 respect to the trailing-edge 4 that an effective water-shed surface 7 is provided for the water leaving the trailing-edge. As shown in Figs. 1 and 3, this is accomplished if this surface in the thicker part of the blade lies 115 in a plane about forty-five degrees from the vertical transverse plane of the hub. The variation in the surface 7 as it leaves the hub and approaches the tip is such that its angular relation with respect to the trailing 120 edge is maintained substantially constant. At speeds less than the normal speed of the ship this surface 7 assists in the propulsion.

It will be understood that the blades, of which there may be two or more, are alike 125 and that the propeller may be either right or left handed.

When the propeller is revolved in the direction of the arrow, Fig. 2, the water strikes the curved faces of the blades and as 130

the latter are so set that the trailing-edges point straight backward, the water is thrust straight backward in lines parallel with the propeller shaft. Likewise, the rearwardly inclined outer part of the blade forces the water straight backward in lines parallel to the shaft. As the thrust forward on the propeller-shaft is equal to the thrust of the water backward, no loss of power occurs except that due to friction of the blades passing through the water.

It will be obvious to the maker of the propeller that the form and arrangement of the blades must be such that all points of the working-faces thereof will force the water backward in straight lines parallel to the shaft and any deviation from this will be a fault in proportion to such deviation. However, variations may be made as to the location of the line A—B at which the constant curvature of the working-face of the blade is terminated. For instance, in high-speed boats, the line A—B may be farther away from the hub while in low-speed boats it is well to locate it nearer the hub.

The object in curving the portion of the blade between the line A—B and the hub in the manner hereinbefore described is to eliminate the churning action usually produced by the blades of the previously known propellers adjacent the hub and to derive an effective forward thrust from the water through which this portion of the blade passes. The portions of the blades near the hub cut through much less water than those portions near the tips and in order to get the same proportional thrust, the water near the hub must be forced backward on an arc of a smaller circle than is required near the tips.

It will be noted that the propeller-blade increases in thickness from the relatively sharp leading edge 3 to the rear portion. The strains are taken up by the thicker portion of the blade and the thickness depends therefore largely upon the size of the propeller and the strains which it must withstand. Due to the construction described, I am able to insure considerable strength in a light propeller, with a consequent saving of a substantial amount of metal.

It will be understood that by the term "approximately seventy-five degrees" as applied in the claims to the length of arc defining the curvature of the thrust-face of the blade, I mean to include arcs of somewhat greater or less lengths and any arc of between, say, sixty and ninety degrees is comprehended within the term used. Preferably, however, the arc is appreciably less than a quarter of a circle.

I claim:

1. A propeller-blade, the thrust-face of which has an arcuate concavity the arc of which subtends an angle of approximately

seventy-five degrees near the hub and the radius of curvature increasing substantially to infinity at the tip.

2. A propeller-blade, the mathematical projection whereof in the plane of rotation 70 is a semi-circular band, the thrust-face of said blade having a concave portion.

3. A propeller-blade, the mathematical projection whereof in the plane of rotation 75 is a semi-circular band, the thrust-face of said blade having an arcuate concavity the arc of which subtends an angle of approximately seventy-five degrees.

4. A propeller-blade, the mathematical projection whereof in the plane of rotation 80 is a semi-circular band, the thrust-face of said blade having an arcuate concave portion near the hub the arc of which subtends an angle of approximately seventy-five degrees.

5. A propeller-blade, the thrust-face of which has an arcuate concavity, the radius of the arc being constant in the proximity of the boss of the propeller and progressively increasing in the proximity of the tip of said 90 blade.

6. A propeller-blade, the mathematical projection whereof in the plane of rotation is a semi-circular band, the thrust-face of said blade having an arcuate concavity of 95 progressively increasing radius as the tip is approached, and such portion of the blade being bent backward out of the plane of rotation.

7. A propeller-blade, the mathematical 100 projection whereof in the plane of rotation is a semi-circular band, the thrust-face of said blade having an arcuate concavity, the radius of the arc being constant in the proximity of the boss of the propeller and progressively increasing in the proximity of the tip, the portion of the blade having the face of varying curvature being bent backward out of the plane of rotation.

8. A propeller-blade, the thrust-face of 110 which has an arcuate concavity, the radius of the arc being constant in that portion of the blade from the boss to a cross-section line approximately midway the length of the blade and progressively increasing from 115 such line to infinity at the tip of the blade.

9. A propeller-blade, the thrust-face of which has an arcuate concavity, the radius of the arc being constant in that portion of the blade from the boss to a cross-section 120 line approximately midway the length of the blade, the arc of this portion subtending an angle of approximately seventy-five degrees, the radius of the curvature progressively increasing from such line to infinity at the tip 125 of the blade.

10. A propeller-blade, the thrust-face of which has an arcuate concavity, the radius of the arc being constant in that portion of the blade from the boss to a cross-section line 130

approximately midway the length of the blade, the arc of this portion subtending an angle of approximately seventy-five degrees, the radius of curvature progressively increasing from such line to infinity at the tip, and the portion of the blade having the face of varying curvature being bent backward out of the plane of rotation.

11. A propeller blade, the mathematical projection whereof in the plane of rotation, is a semi-circular band, the thrust-face of said blade having an arcuate concavity, the radius of the arc being constant in that portion of the blade from the boss to a cross-section line midway the length of the blade, the arc of this portion subtending an angle of approximately seventy-five degrees, the radius of curvature progressively increasing from such line to infinity at the tip, and
- 15 20 the portion of the blade having the face of

varying curvature being bent backward out of the plane of rotation.

12. A propeller-blade having a relatively sharp leading-edge and a relatively thick rear portion, the under part of said rear portion extending axially beyond the trailing-edge substantially along the whole length thereof to provide a water-shedding surface.

13. A propeller-blade having a relatively sharp leading edge and a relatively thick rear portion, the under part of said rear portion extending axially beyond the trailing edge substantially along the whole length thereof to provide a water-shedding surface, said surface having a constant angular relation to the trailing edge.

In testimony whereof I affix my signature.

ISAIAH L. ROBERTS.
